WELL-TREATING TOOL

Morris W. Frack, Tulsa, Okla., assignor to The Dow Chemical Company, Midland, Mich., a corporation of Michigan

Application April 30, 1941, Serial No. 391,061

2 Claims. (Cl. 166—20)

This invention relates to an improvement in a well treating tool adapted to deliver one or more high velocity streams or jets of acid solution into a well bore against the face of the formation, well casing, or other parts of the well.

In treating wells wherein a tool is employed to direct a series of high velocity streams of acid against various portions of the well bore, it often-times happens that it is desirable to seal the orifices through which the acid issues during the period the tool is being positioned at the desired location in the well bore. Placing a seal over the orifices is desirable in order to eliminate the possibility of sand or mud entering the tool through the orifices and exerting a plugging action by becoming lodged in the small passageways through which the fluid passes. It is also desirable to prevent entry of fluid into a treating tool of this type since any fluid which enters the tool must be forced therefrom through the small orifices therein, and as a result more time is required to complete a treatment. Such sealing means should, however, be readily removable after the treating tool has been positioned at the desired location in the well bore.

It is, therefore, the principal object of this invention to provide an acid treating tool having sealing covers for the orifices through which the acid solution is to be ejected, said covers being characterized by being readily removable after the acidizing tool has been positioned in the well bore at the desired location.

Other objects and advantages will be apparent as the description of the invention proceeds.

The invention will be more readily understood from the following description taken in connection with the accompanying drawing wherein:

Fig. 1 is a somewhat diagrammatical elevational view of a well bore showing the tool positioned adjacent a section of the formation it is desired to treat.

Fig. 2 is an enlarged fragmentary view partly in cross section showing in more detail the construction of the acidizing tool.

Fig. 3 is a further enlarged cross-sectional view of an orifice member showing the sealing cover in place.

Fig. 4 is a perspective view of the sealing disk adapted to cover the orifice.

Fig. 5 is a cross-sectional view taken along lines 5—5 of Fig. 4.

As shown in Fig. 1, the acidizing tool 1 is suspended in the well bore 2 by means of a suitable conduit 3. High velocity streams of acid 4 are

shown issuing from the tool 1 and impinging against the face of the formation at 5.

In the more detailed view of Fig. 2 the housing 6 of the acidizing tool is shown connected at its upper end to a swage nipple 7 by means of coupling or collar 8. The reduced end of nipple 7 is threaded for connection to the conduit 3 which may suitably be the well tubing. At intervals the housing is provided with plug members 9 which are attached to the housing as by welding. The plug members 9 are internally threaded for threaded engagement with the orifice members 10 through which the acid issues into the well bore.

In the enlarged detailed view of Fig. 3 an orifice member 10 is shown with a small orifice or port 11 centrally located therein. The orifice 11 is counterbored at the outlet so as to form an enlarged recess 12 into which a dome-shaped readily acid-soluble metal disk 13 is pressed to act as a seal for the orifice.

The dome-like shape of the readily acid-soluble metal disk will be more readily appreciated with reference to Figs. 4 and 5.

In the operation or use of the tool the acid-soluble metal disks 13 are pressed into the counterbored recesses 12 and the tool lowered into the well on the well tubing or other suitable conduit to the desired location. Thereafter the acid solution, which will ordinarily be hydrochloric acid of from 5 to 25 per cent concentration suitably inhibited against corrosive attack on iron or steel, will be introduced into the tool and upon coming into contact with the readily acid-soluble sealing disks will rapidly dissolve them so that the acid solution will have ready access to the well bore. Pressure will then be applied to the acid to force it from the tool in high velocity streams or jets. The pressure employed may vary quite widely as from a few hundred up to 3,000 pounds per square inch.

The acid solution to employ will, of course, depend upon the use for which it is intended. In general, when treating a producing formation or bringing about the disintegration of cement, hydrochloric acid or a mixture of hydrochloric acid and hydrofluoric acid will be employed.

The readily acid-soluble metal sealing disks are most suitably made of magnesium metal. The term "magnesium" used herein and in the appended claims is intended to include the magnesium of commerce which contains small amounts of impurities such as iron, copper, and the like as well as alloys of magnesium in which this metal is the predominant constituent. Mag-

nesium is very readily soluble in most acids and is very rapidly dissolved by both uninhibited and inhibited hydrochloric acid.

The sealing disks employed for the purpose at hand may vary quite widely in thickness. Generally illustrative of a suitable thickness is from $\frac{1}{8}$ to $\frac{1}{4}$ of an inch. It has been found desirable to form the disks so that they will have a dome-like shape such as is illustrated, since a larger area will be exposed to the action of the acid, assuring more immediate and complete removal of the sealing covers.

I claim:

1. In a well treating tool adapted to deliver a high velocity stream of acid to the well bore, the combination which includes a housing adapted to be connected to the well tubing, plug members attached to the housing having orifices therein

through which acid may pass from the housing into the well bore, said plug members being counterbored about the orifices, and magnesium disks engaging the counterbored recesses in the plug members in sealing relation.

2. In a well treating tool adapted to deliver a high velocity stream of acid to a well bore, the combination which includes a conduit, a housing adapted to be connected to the conduit, plug members attached to said housing having orifices therein through which acid may issue from the housing into the well bore, said plug members having counterbored recesses about the orifices, and dome-shaped magnesium metal disks engaging the counterbored recesses in the plug members in sealing relation.

MORRIS W. FRACK.
